UNITED STATES PATENT OFFICE.

OLIVER S. JENNINGS, OF MANSFIELD, OHIO, ASSIGNOR TO WESTINGHOUSE ELECTRIC & MANUFACTURING COMPANY, A CORPORATION OF PENNSYLVANIA.

CIRCUIT-BREAKER APPARATUS.

Application filed August 6, 1927. Serial No. 211,035.

My invention relates to circuit breaker apparatus and particularly to circuit breaker apparatus wherein a disconnect switch serves to disconnect a circuit breaker, auto-starter or contactor switch, from the feed conductors, and wherein interlocked mechanism is provided for preventing opening of the disconnecting switch prior to the opening of the circuit breaker devices.

10 An object of my invention is to provide a circuit breaker apparatus, wherein a snap action disconnecting switch is interlocked with the relay or controlling coil of a circuit breaker prior to the opening movement of the 15 disconnecting switch.

Another object of my invention is to provide circuit breaker apparatus having the above-noted characteristics, wherein a standard snap action or quick break disconnecting 20 switch is provided with an auxiliary control switch that is actuated to cause operation of the circuit breaker trip relay to open the circuit breaker, and wherein the operating means for the disconnecting switch so controls the auxiliary control switch, that it causes the circuit breaker to open in advance 25 of the movement of the operating means of the disconnecting switch to the position in which it releases the disconnecting switch.

30 A further object of my invention is to provide a circuit breaker apparatus, wherein standard quick break snap action disconnecting switches may be provided with a simple auxiliary control switch that may be mounted 35 within the housing for the disconnecting switch, and which is actuated by the operating handle of the disconnecting switch.

These and other objects that will be made apparent throughout the further description 40 of my invention, are obtained by means of the apparatus hereinafter described and illustrated in the accompanying drawings, where- in:

Figure 1 is a plan view of a standard snap action disconnecting switch having a portion of the cover broken away to expose the auxiliary switch,

Fig. 2 is a side elevational view of the disconnecting switch shown in Fig. 1, showing a portion of the handle in section and the snap action operating mechanism for the disconnecting switch in side elevation, and

Fig. 3 is a wiring diagram showing the manner in which the disconnecting switch is connected with the circuit breaker.

Referring to the drawings, the apparatus includes a sheet metal housing 4 having a hinged cover 5 for enclosing the switch mechanism which includes an insulating base 6, upon which hinge jaws 7 of a disconnecting switch are mounted. Switch blades 8 are pivoted to the hinge jaws 7 and are adapted to engage contact jaws 9 mounted on the base 6. An operating lever or bail 11 is connected to the switch blade 8 by means of insulating arms 12 that are riveted to the switch blade 8 and which are provided with openings for receiving the bent portion of the bail 11. This construction of disconnecting switch is well known in the art, and it is believed that further description thereof is unnecessary.

The switch operating bail 11 extends through a bearing opening 13 in a side wall of the housing, the operating handle and actuating mechanism being supported upon the extending portion 14 of the bail in a manner to be hereinafter described.

The switch operating mechanism herein illustrated is substantially identical to the operating mechanism disclosed in Patent No. 1,606,801, issued to Hubert K. Krantz, filed September 25, 1924, and no claim is made to the specific disconnecting switch or operating mechanism which is hereinafter described.

The operating handle 15 is hollow and made of cast metal and is pivoted upon the bail extension 14, and is relatively rotatable thereon. A driving dog 16 is fixed to the bail end 14 and is provided with a pair of pins 17 and 18, that extend into arcuate slots 19 and 21 of a cam plate 22, that is disposed within the operating handle and which is connected to a spring 23 at the point 24, the spring being attached at its outer end to a pin 25 secured to the operating handle.

The spring 23, when the parts are in the closed position shown in Fig. 2, serves to draw the cam plate toward the free end of the operating handle, such movement being limited by reason of the engagement of the ends 26 and 27 of the slots 19 and 21, respectively, with the pins 18 and 17, respectively. The movement of the cam plate 22 is further limited by the shoulders 28 and 29 on the enlarged portion of the cam plate which engage shoulders 31 and 32 of the operating handle.

A stud 33 that is attached to the side wall of the housing, projects through the notches 110

19 and 21 in the cam plate, and serves to prevent rotary driving movement of the cam plate until the point 34 on the cam plate passes the center of the stud 33.

5 It will be understood that it is the function of the cam plate to rotate the dog 16 through the medium of the pins 17 and 18, and the ends of the slots 27 and 28, respectively, after the operating handle 15 has 10 moved the point 34 of the cam plate past the center of the stud 33. As shown in Fig. 2, the parts of the switch mechanism are in the closed position. To open the switch, the operating handle is rotated counter-clockwise. The spring 23 tends to rotate the cam plate 22 counter-clockwise, but this movement of the cam plate is prevented by reason 15 of the engagement of the cam surface 35 with the stud 33. Since the curvature of the cam 20 edge 35 is concentric to the pin 17 on the dog 16, the cam plate will rotate counter-clockwise about a center coincident with the pin 17 without exerting any tendency to move the pin 17 or the dog 16. The spring 23 will 25 be expanded during this operation and no movement of the cam plate, tending to move the pin 17, will occur until the point 24 of the cam has passed the center of the stud 33. At this time, the center of the operating 30 handle 15 will occupy the position A indicated in dot and dash lines. Immediately after the point 24 passes the center of the stud 33, the spring will draw the cam plate toward the outer end of the handle, thus rotating 35 the cam plate 22 counter-clockwise with a snap action, and drawing the pin 15 and the dog 16 with it, turning them counter-clockwise and thus causing the switch to open with a snap action. The operating 40 handle 15 will then occupy the position B shown in dot and dash lines.

In order to close the switch, the operating handle is rotated clockwise. Closing movement of the switch will be arrested by 45 the cam edge 36, which corresponds to the cam edge 35, until the point 24 passes the center of the stud 33. The curvature of the cam edge 36 is concentric with the center of the pin 18 and, consequently, the same 50 cam plate action will result as previously described, except that its movement will be in the reverse direction. After the cam point 24 has passed the center of the stud 33, the cam plate will rotate in a clockwise direction 55 with a snap action, drawing with it the pin 18 and the dog 16, thus causing the switch to be closed with a snap action after the handle has moved a predetermined distance toward closed position. The operation of 60 the mechanism just described is fully set forth in the above-noted patent, and it is believed that no further description of the mechanism is required.

The apparatus just described is a standard 65 snap action, quick make and quick break dis-

connecting switch of the enclosed type. Such switches are commonly used to disconnect the feed conductors from a circuit breaker. It is essential that the circuit breaker be opened prior to the opening of the disconnecting switch, for the reason that the disconnecting switch is not usually designed to interrupt the large capacity circuits.

Circuit breakers are better adapted to interrupt the circuit under full load, and therefore should be opened in advance of the disconnecting switch. The purpose of the disconnecting switch is to disconnect the circuit breaker from the feed conductors, in order that the circuit breaker may be isolated from the line and live conductors when it is desired to inspect or repair it.

Referring to Fig. 3, the circuit breaker 37, for the purpose of illustration, is provided with a holding coil or relay 38 that retains 85 the circuit breaker in closed position so long as current is supplied to the holding coil. When the circuit is interrupted, a spring 39 causes the circuit breaker to open by collapsing the toggle 41. The disconnecting 90 switch blades 8 are connected in series with the circuit breaker 37, and an auxiliary control switch 42 serves to control the circuit through the holding coil 38. When the disconnecting switch is connected to a circuit breaker that is retained in closed position by a latch, the auxiliary switch is connected in the usual trip coil circuit.

In my present invention, it is an object to so interlock the auxiliary switch 42 with 100 the operating means of the disconnecting switch, that the switch 42 will be caused to open prior to the opening operation of the disconnecting switch.

The auxiliary control switch 42 is pivotally mounted on the side wall of the housing and is adapted to engage contacts 43 and 44 when rotated. The switch 42 is provided with a shaft 45 which extends through the side wall of the housing and is provided with an 110 operating lever 46 that is adapted to engage the operating handle 15 as indicated in Fig. 2. A spring 47 is attached at one end to the side wall of the housing, and at the other end to the lever 46 in such manner that it normally tends to rotate the switch 42 counter-clockwise to open position.

As shown in Fig. 2, the operating handle 15 is in the closed position and is holding the switch 42 in closed position by reason of 120 the engagement of the handle 15 with the lever 46. The arrangement of the auxiliary switch 42 and the lever 46 is such that the operating handle will permit the spring 47 to open the switch 42 when the operating handle 15 has been rotated to the position C indicated in dot and dash lines in Fig. 2.

When the switch 42 has opened the control circuit through the coil 38, the circuit breaker will open. It will be noted that the 125

opening of the auxiliary switch occurs prior to the opening of the disconnecting switch blades 8, since the disconnecting switch will not be snapped open until the operating handle has reached the position A.

By reason of the construction just described, it will not be possible to open the disconnecting switch without first having caused the circuit breaker to open. The circuit breaker will be automatically opened when the operating handle has been moved to the position C. Therefore, the circuit breaker will be fully open before the operating handle has reached the position A.

Since the holding coil cannot be energized without first closing the auxiliary switch 42, the circuit breaker cannot be closed until the disconnecting switch has been closed. It will be understood that when the operating handle of the disconnect switch is moved to closed position, it will cause the switch blades 8 to be snapped to closed position prior to closing of the holding coil. The disconnecting switch will, therefore, be closed prior to the closing of a circuit breaker and, therefore, there is no danger of the circuit breaker being closed in advance of the closure of the disconnecting switch. A push button switch 48 is connected in the control circuit for normally controlling the operation of the circuit breaker.

While I have illustrated but one embodiment of my invention, it will be apparent to those skilled in the art that various changes, modifications, substitutions, additions and omissions may be made in the apparatus illustrated without departing from the spirit and scope of my invention, as set forth in the appended claims.

I claim as my invention:

1. The combination with a switch having means for actuating it to open position with a snap action after the operating mechanism has moved to a predetermined position, of a control switch retained in one of its posi-

tions by the operating mechanism and adapted to be moved to another position to cause actuation of a cutout device, in advance of the movement of the operating mechanism to the said predetermined position.

50

2. The combination with a switch having means for actuating it to open position with a snap action after the operating mechanism has moved to a predetermined position, of a control switch yieldingly biased to one of its operating positions and retained in its other operating position by the said operating mechanism and adapted to be moved by the biasing means to the first operating position in advance of the movement of the operating mechanism to the said predetermined position.

55

3. The combination with a snap action switch having a power storing means for opening the switch with a snap action actuated by an operating means and having means for releasing the switch for actuation by the power storing means when the operating means has moved to a predetermined position, of a control switch for a relay controlled by the operating means and adapted to be actuated to an operative position for causing actuation of the relay in advance of the movement of the operating means to the said predetermined position.

60

70

4. The combination with a switch provided with an operating means and having means for actuating it to open position with a snap action after the operating means has moved to a predetermined position, of a control switch for a relay controlled by the operating means and adapted to be actuated to an operative position for causing actuation of the relay in advance of the movement of the operating means to the said predetermined position.
